UNITED STATES PATENT OFFICE

JAMES L. LANE, OF CHICAGO, AND ALFRED H. MOORE, OF OAK PARK, ILLINOIS, ASSIGNORS TO LINK-BELT COMPANY, OF CHICAGO, ILLINOIS, A CORPORATION OF ILLINOIS

MACHINE FOR MAKING SPIRAL CONVEYERS

Application filed April 13, 1928. Serial No. 269,716.

This invention relates to improvements in machines for making spiral conveyers and has for one object to provide a new and improved machine for simultaneously forming the spiral or helical flight from bar or strip stock and as it is formed winding or wrapping it about the central shaft of the conveyer. Another object is to provide a device wherein the dimensions of the conveyer flight 10 may be accurately controlled and wherein both the inner diameter and outer diameter and the pitch may be held to close tolerances.

Another object is to provide a device wherein the metal forming rolls may be so associated with the shaft upon which the spiral flight is placed that the shaft may be fed into relation with the helical flight as the flight is formed without interference by the rolls. Other objects will appear from time to time 20 throughout the specification and claims.

The invention is illustrated more or less diagrammatically in the accompanying drawings, wherein—

Figure 1 is a longitudinal vertical section 25 through a machine adapted to carry out the invention;

Figure 2 is a front elevation of the machine;

Figure 3 is a section along the line 3—3 30 of Figure 2;

Figure 4 is a section along the line 4—4 of Figure 2;

Figure 5 is a section along the line 5—5 of Figure 1;

Figure 6 is a section along the line 6—6 of Figure 5;

Figure 7 is a section along the line 7—7 of Figure 6;

Figure 8 is a section along the line 8—8 of Figure 5.

Like parts are indicated by like characters throughout the several figures.

A is a supporting frame. In it is mounted for rotation the hollow cylindrical roll A¹. This roll is supported at both ends in the frame as indicated and has at one end a cupped or concave working face A². A³ is a thrust bearing. The frame A is associated with an adjustable thrust block A⁴ to prevent longitudinal movement of the roll. A⁵ is a

hub mounted on the roll A¹ between its two bearings in the frame A and this hub carries a bevel gear A⁶.

B is a generally cylindrical or very slightly tapered roll. Its axis of rotation is at 55 right angles to the axis of rotation of the roll A¹ and its cylindrical working face B¹ is in opposition to the working face of the roll A¹, the end of the roll being substantially tangential to the inner diameter of the roll A¹. This roll B is located at the end of a drive shaft B² mounted for rotation in the frame A, being supported in bearings at both ends thereof. B³ is a hub on the shaft B² between said bearings and it carries a bevel gear B⁴ in mesh with the gear A⁶. The shaft B² extends upwardly and may be driven by any suitable means not here shown which drive the shaft E carrying a beveled gear E¹ in mesh with the bevel gear E² on the shaft 60 B². E³ is the sprocket on the shaft E¹ driving a chain E⁴ which in turn drives a sprocket E⁵ to operate the shaft feeding and rotating mechanism, the driving of this shaft resulting in driving the rolls A¹ and B in unison. 65

Projecting laterally from the frame is a stock guide. This stock guide takes the form of a solid or channeled pocket C through which a strip of bar stock C¹ may be fed and guided into the space between the opposed 70 working faces of the rolls. This stock guide is removable, being held in place by the cap screws C² so that different or adjustable guides may be provided for different sizes of conveyer flights. No feeding means are provided in connection with the stock guide. Once a stock has been passed in through the guide and engages the roll, the rolls themselves draw in stock at the rate at which it is to be worked in the manner usual to rolling 75 mill practice.

The flight guide comprises a base D bolted to the frame A by means of cap screws D¹. From it projects upwardly the bracket D² which carries a guide head D³ located in front 80 of the roll A¹. Associated with the bracket D² is a removable bracket D⁴ which bracket is held on the member D² by the cap screws D⁵. D⁶ is a guide head on the member D⁴ in opposition to the guide head D³. These two 85

guide heads cooperate to form a helical guide slot so positioned as to receive the flight after it has been passed between and formed by the rolls and guide it along a helical path away from the rolls, giving it the desired pitch.

E is a housing containing a shaft feeding and rotating mechanism located in line with the hollow cylindrical roll and containing means adapted to feed the shaft longitudinal 10 ly through the hollow roll to cause the rate of rotation and rate of longitudinal feed of the shaft to correspond to the rate of feed and rotation of the finished flight.

In commercial practice spiral conveyers 15 have their spiral flights mounted on pipe or shafts and they are so referred to in the trade. In this specification we refer only to shaft using that in its generic sense as applied to any element whether slotted as a cold 20 rolled shafting or hollow as a pipe which serves as a central supporting shaft about which spiral flights are wound.

Mounted for rotation in the housing E is a pipe feeding shaft F, which shaft carries 25 and is driven by the sprocket E⁵. This shaft carries a pinion F¹ in mesh with a pinion F² on the shaft F³ and both the shafts F and F³ carry grooved drive heads F⁴ F⁵. These drive heads engage opposed sides of the pipe 30 or central shaft about which the spiral flight is to be wound and since the drive is positive through chain and gear from the feeding and flight forming rollers, the relation between the forward movement of the shaft and the feeding out movement of the spiral will be 35 fixed.

On the end of the shaft F³ is a gear G in mesh with a pinion G¹ on the stub shaft G². The inner end of the stub shaft carries a mitre 40 gear G³ in mesh with an annular mitre gear G⁴, which gear has a hub G⁵ and is mounted for rotation in the boss G⁶. This hub G⁵ is hollow to permit the pipe to pass through and is provided with a plurality of tangential 45 pockets G⁷ in which travel over-running clutch balls G⁸ forced inwardly against the pipe by springs G⁹ whose tension is adjusted by the set screws G¹¹. The movement of this hub driven as it is by a train of gears from 50 the shaft F is in the direction shown in the arrows in Figure 6 and Figure 7 and rotates the pipe in unison with the rotary feed required to wind the spiral flight about it. At the same time the jaw or grip balls offer 55 no serious resistance to the forward longitudinal movement of the pipe.

Thus the spiral conveyer flight is fed out by friction drive and the pipe itself is fed longitudinally and rotated by friction drive. 60 Various driving elements are tied together by positive chain and gear train, the only possible slippage being at the drive points themselves and any such slippage will be compensated for in view of the fact that all drives 65 are equalized to give uniform operation.

The guide through which the helical flight is fed after it is formed insures that the flight will assume a proper pitch as it is wound about the shaft. In fact even though the shaft were not present this guide would insure proper pitch dimensions and since the parts are so arranged that the inner diameter of the helix grips the shaft snugly, it is possible to operate the device and assemble the spiral conveyer without any separate feed means for the shaft. The engagement of the helical flight with the shaft will as a result of the forward and rotary movement imparted to it by the rolls draw out and rotate the shaft so that under some conditions the separate feed may be dispensed with.

Also if the drive for the shaft which rotates it and which moves it longitudinally is properly correlated with the speed at which the rolls discharge the flight, it is possible to omit the guide because as soon as the flight snugly hugs the shaft if the shaft is given the correct movement the engagement of the flight with the shaft will result in properly forming and positioning the flight on the shaft. However, under ordinary conditions, experience shows that it is best to use both the positive feed for the shaft and the guide for the helical flight. The positive feed is shown diagrammatically at E, taking the form of a sprocket chain which operates the feed mechanism in coordination with the rolls.

The contours of the opposed faces of the rolls are fixed empirically. In general the solid roll is cylindrical or very slightly conical or tapered. The hollow or tubular roll is concave and it might be conical but preferably the surface is a curved surface, the radius of curvature of the surface decreasing outwardly. When these contours are established different thicknesses of metal may be taken care of by changing the distance between the working faces of the rolls and this is done by unscrewing or screwing in the holding sleeve. The forward movement of the hollow roll is limited by the shoulder as indicated. When the holding sleeve is backed off the hollow roll clears the shoulder but is held in place by the metal squeezed between the two rolls and no separate means are needed for holding it back against the sleeve.

The use and operation of this invention are as follows:

The shaft is fed in through the hollow roll until it normally extends beyond the working faces of the rolls. This may be done either by hand or by merely allowing the shaft feeding mechanism when used to operate and this shaft feeding mechanism may be independently driven or driven in unison with the rolls though if independently driven it should be a frictional drive so that slippage may take place to enable the shaft feed and the flight feed to correspond. The operator then feeds a strip of stock and it may be bar stock in

straight lengths or strip stock wound in rolls as the case may be. The end is fed in through the guide into engagement with the working face of the rolls. As the rolls rotate they draw the flat flight forming stock in between their working faces. It will be noted that the distance between the faces decreases outwardly so that the flight as it is formed is thicker toward the center than toward the outer periphery. This elongates the outer periphery of the flight and causes it to form a general spiral. The spiral flight thus formed is preferably guided through the fixed guides to give it proper pitch. As this flight travels out through the guide it is wound about the shaft, the shaft being fed forward and rotated to conform approximately to the rate at which the flight is formed. When a flight of the desired length has been wound about a shaft, it is only necessary to cut off the stock, stop feed of the flight forming stock, run the shaft on through the machine and cut it off in proper length.

An arrangement such as this makes it possible to keep in stock only long lengths of shaft and flight forming stock. The operator can run the machine until a flight of the right length has been formed, cut off the length of flight, withdraw the shaft and leave the apparatus in readiness for the next lot. It is not necessary then to form predetermined lengths of flights which must be cut off in lengths to suit, with the stub ends wasted.

The relation between the forming rolls, the guide and the shaft feeding means are such that the flight is wound upon the shaft in the position which it is to occupy and no further manipulation or adjustment between the flight and the shaft is needed.

40 We claim:

1. A machine for making spiral conveyers comprising a hollow roll having an annular working face on the end thereof, a roll mounted for rotation on an axis generally perpendicular to, and terminating substantially in line with the inner periphery of the hollow roll, and a support therefor out of line with the working face of the hollow roll, means for longitudinally feeding a shaft through the hollow roll and for rotating it.

2. A machine for making spiral conveyers comprising a hollow roll having an annular working face on the end thereof, a roll mounted for rotation on an axis generally perpendicular to, and terminating substantially in line with the inner periphery of the hollow roll, and a support therefor out of line with the working face of the hollow roll, means for longitudinally feeding a shaft through the hollow roll and for rotating it, in unison with such longitudinal feed.

3. A machine for making spiral conveyers comprising a hollow roll having an annular working face on the end thereof, a roll mounted for rotation on an axis generally

perpendicular to, and terminating substantially in line with the inner periphery of the hollow roll, and a support therefor out of line with the working face of the hollow roll, means for guiding a strip of material into the space between the working face of the rolls and means for guiding a conveyer flight formed from such strip by the action of the rolls along a spiral path parallel with the axis of the hollow roll, means for feeding a shaft longitudinally through the hollow roll and through the guiding means and rotating the shaft whereby the conveyer flight is wound about the shaft as it is formed.

4. A machine for making spiral conveyers comprising a hollow cylindrical roll having a working face on the end thereof and adapted to permit longitudinal feed of a shaft therethrough, a roll having a working face on the side thereof in opposition to the working face of the hollow roll and terminating adjacent the periphery of the shaft which is fed through the hollow roll, a guide associated with said rolls and direct it in a spiral path around the shaft and means for rotating a shaft and feeding it longitudinally through the hollow roll to permit a formed conveyer flight to be progressively mounted thereabout.

5. A machine for making spiral conveyers comprising a hollow roll having an annular working face on the end thereof, a roll mounted for rotation on an axis generally perpendicular to, and terminating substantially in line with the inner periphery of the hollow roll, means for longitudinally feeding a shaft through the hollow roll and for rotating it in unison with such longitudinal feed.

6. A machine for making spiral conveyers comprising a hollow roll having an annular working face on the end thereof, a roll mounted for rotation on an axis generally perpendicular to, and terminating substantially in line with the inner periphery of the hollow roll, means for guiding a strip of material into the space between the working face of the rolls and means for guiding a conveyer flight formed from such strip by the action of the rolls along a spiral path parallel with the axis of the hollow roll, means for feeding a shaft longitudinally through the hollow roll and through the guiding means and rotating the shaft whereby the conveyer flight is wound about the shaft as it is formed.

7. A machine for making spiral conveyers comprising rolls adapted to form and feed out a continuous spiral flight, a shaft associated with said rolls about which the flight is wound and fixed, means for feeding the shaft forwardly and rotating it in unison with the feeding out of the spiral flight and a positive driving connection between the flight feeding and the shaft feeding means.

8. A machine for making spiral conveyers comprising rolls adapted to form and feed

out a continuous spiral flight, a shaft associated with said rolls about which the flight is wound and fixed, means for feeding the shaft forwardly and rotating it in unison with the feeding out of the spiral flight and a positive driving connection between the flight feeding and the shaft feeding means, the shaft feeding means comprising separate means for feeding the shaft longitudinally, 10 separate means for rotating the shaft and a driving connection between such means.

Signed at Chicago, in the county of Cook and State of Illinois, this 24th day of March, 1928.
